CHARLES M. HATCHER, OF OAKLAND, CALIFORNIA, ASSIGNOR OF ONE-HALF TO
JOSEPH L. ROSS, OF REDWOOD CITY, CALIFORNIA.

MILK-BOTTLE HOLDER.

1,408,195.

Specification of Letters Patent. Patented Feb. 28, 1922.

Application filed November 22, 1919. Serial No. 339,931.

To all whom it may concern:

Be it known that I, CHARLES M. HATCHER, a citizen of the United States, residing at Oakland, in the county of Alameda and State of California, have invented certain new and useful Improvements in Milk-Bottle Holders, of which the following is a specification.

This invention relates to improvements in bottle-holders and more particularly to a device for holding the standard bottles in which milk is delivered.

The principal object of the invention is to provide a holder which will permit a bottle being placed therein but which will prevent its unauthorized removal therefrom.

Another object is to provide a device which is simple in construction, having no moving parts and requiring no key to unlock.

A further object of the invention is to provide a holder of the character described which will prevent flies, cats and other animals from touching or licking the top of the bottle and transferring disease germs thereto.

A still further object is to provide a holder of the character described which is constructed so as to prevent the insertion of a tool in such a way that the holder may be sprung, unlocked or deranged and an unauthorized removal of the bottle effected.

With these and other objects in view the invention consists of certain novel features of construction, combinations and arrangements of parts herein described and more specifically pointed out in the appended claims.

Reference being had to the accompanying drawing forming a part of the specification,

Figure 1 is a view in section through a door showing the manner in which my improved bottle holder is installed.

Figure 2 is a view in longitudinal section of the improved holder.

Figure 3 is a view in longitudinal section showing the upper part of a bottle positioned therein.

Figure 4 is a transverse sectional view showing a bottle positioned therein.

Figure 5 is a bottom plan view of the holder.

Denoting corresponding parts in the several views by the same numerals of reference, the device consists of an elongated body de-

noted generally by 1. This body comprises the flat top 2 and the flanged sides 3, the latter being joined in a semicircular end, the width across this portion of the device is slightly more than the outside diameter of 60 the top of the milk bottle 6.

The opposite end of the body is open and the sides adjacent the open end are provided with inwardly formed ribs 5. These ribs are formed a sufficient distance below the top 65 2 to allow the bead 7 around the bottle top to fit in the recess thus formed between the rib and the top 2.

Attached to the inside of top 2 by means of rivets 9 is a flat resilient strip 8. This 70 strip is fixed only at the end adjacent the closed end of the body, the opposite end 10 being left free and made to project downwardly. The standard milk bottles are formed with a recessed top 12 and the end 75 10 is preferably rounded to conform to the curvature 2 of the recess. The sides 3 are provided with one or more holes 14 by which the holder may be attached to a door frame 15 with the open end of the body adjacent 80 to the door 16.

In use the device is positioned with the open end adjacent a door, window or other movable part, and when delivering milk the top of the bottle is inserted into the rear 85 end of the holder and is then given a slight forward movement towards the open end. This causes the bead of the bottle top to engage the shoulder formed by the ribs 5. As the bottle is moved forwardly the spring 8 90 is raised until such a position is reached that the free end drops into the recess 12.

This engagement between the end of the spring and the recess in the head of the bottle prevents the latter from being moved 95 toward the closed end 4, while the ribs 5 prevent it from being pulled downwardly.

To remove the bottle it is only necessary to open the door 16 and pull the bottle out through the open end of the device. Holes 100 14 may be provided in both sides so that the device may either be used on the right or left hand side of the door; when the bottle is in position, it prevents the removing of the screws and the carrying away of the device along with the bottle.

Thus I have provided a very simple and effective device for holding milk bottles. It prevents the bottles of milk from being stolen and also prevents stray animals from 110

spoiling the milk or from spilling it by knocking over the bottle. It is also desirable because it requires no key or other locking means either by the delivery-man or by the consumer. By having the holder closed at its outer end by the end wall 4 the insertion of a tool to effect the moving of the spring 8 out of locking position, is prevented. This end 4 extends considerably below the upper 10 end of the bottle and the upper end of the bottle is held in close proximity to the top 2 of the holder. By this arrangement cats and other animals are prevented from licking and transferring germs unto the top of 15 the bottle and flies are likewise prevented from crawling onto the bottle at the top thereof.

Having thus described my invention I claim as new and wish to cover by Letters 20 Patent:

1. A holder for a bottle having an annular bead around its top, comprising a top plate, sides extending downwardly therefrom and being arranged to form a closed 25 end, longitudinal ribs found on the inside of said sides terminating short of said closed end and adapted to engage the bead on said bottle and spring means adapted to prevent the withdrawal of the bottle held by said 30 ribs.

2. A holder for a bottle having a bead around its top, comprising a body having a longitudinal cavity closed at one end and open at the opposite end, ribs within said 35 cavity adjacent the open end and spaced from said closed end adapted to engage the bead on the bottle and spring means adapted to engage the mouth of the bottle and prevent it moving toward the closed end of 40 said cavity.

3. A holder for a bottle having an annular bead upon its top comprising a top plate, side walls extending downwardly therefrom to form a longitudinal recess to 45 receive the top of said bottle, ribs on said side walls extending from points spaced inwardly from certain ends of said side walls to the other ends of said walls and adapted to engage the under side of said bead and a spring strip carried by the top plate and projecting downwardly therefrom.

4. A holder for a bottle having an annular bead around its top comprising a top plate, side walls formed integrally therewith, an end wall formed integrally with 55 said top plate and said side walls, inwardly extending ribs formed on said side walls, said ribs being adapted to engage under said bead and the end thereof forming in cooperation with said end wall an opening to 60 permit the insertion of said bead above said

ribs, a flat spring strip attached to said top plate adjacent the closed end of the holder and extending downwardly toward the opposite end, said spring strip being 65 adapted to engage the bottle and prevent its movement toward the closed end of the holder.

5. A holder for a bottle having an annular bead at its top, comprising a top plate, 70 an end wall extending downwardly from said top plate, side walls on the top plate joined to said end wall, inwardly extending portions on said side walls arranged to engage under the bead of said bottle, said 75 side walls having the ends thereof adjacent said end wall spaced apart sufficiently to permit of the upward insertion of the beaded portion of the bottle into a position between said side walls, whereby the bottle 80 may be moved to engage said inwardly extending portions and means within said holder arranged to engage a bottle supported on said inwardly extending portions and preventing its movement toward said 85 end wall.

6. A device into which the beaded upper end of a bottle is adapted to be inserted, comprising a holder closed on its top, sides and at one end, the sides of said holder adjacent 90 the closed end being spaced apart sufficiently to permit of the upward insertion of the bottle therebetween, the remaining portions of said sides being spaced apart at points above the lower edges of said sides a distance less 95 than the diameter of the beaded portion of the bottle, so as to engage under the beaded portion of a bottle moved between said remaining portions and means in said holder which when the beaded portion of the bottle is engaged by said last named portions of the sides will prevent movement of said bottle into position between the first named portions of said sides.

7. A holder for a bottle having an annular bead, comprising a top plate, side walls extending downwardly from the top plate, an end wall extending downwardly from the top plate, ribs formed on said side walls adapted to engage under the bead of 105 said bottle, certain ends of said ribs being spaced from said end wall sufficiently to permit of the upward insertion of the bead of said bottle between said side walls and to a point above said ribs, and means within 110 the holder for engagement with the bottle when the bead thereof is supported by said ribs for preventing movement of said bottle toward said end wall.

In testimony whereof I affix my signature. 120

CHARLES M. HATCHER.
